UNITED STATES PATENT OFFICE.

HENRY C. PRIVETT, OF LONG BEACH, CALIFORNIA, ASSIGNOR TO PACIFIC CANNING MACHINERY COMPANY, OF LONG BEACH, CALIFORNIA, A CORPORATION OF CALIFORNIA.

CAN-CONVEYER.

1,225,172.

Specification of Letters Patent.

Patented May 8, 1917.

Application filed April 29, 1915, Serial No. 24,647. Renewed March 19, 1917. Serial No. 155,944.

To all whom it may concern:

Be it known that I, HENRY C. PRIVETT, a citizen of the United States, residing at Long Beach, in the county of Los Angeles and State of California, have invented a new and useful Can-Conveyer, of which the following is a specification.

An object of this invention is to make provision whereby containers such as cans 10 can be suitably conveyed during cooking or other operations.

Another object of this invention is the production of a device of this character in which a maximum number of cans may be 15 operated on in a minimum amount of space, thereby effecting economy in the amount of space required for the operation.

Another object is to produce a device in which cans may be treated with steam in 20 minimum amount of space for a definite regulable interval of time.

Another object is to provide a construction whereby the rate of discharge of cans from the tank may be different than the rate of 25 travel of the cans in the tank.

Another object is to provide a construction whereby the cans may be retained in the tank, while the device is in operation, for a longer period of time than that required 30 for the can to travel from the inlet to the outlet of the tank, so as to prolong the cooking of the contents of the cans.

Another object is to make provision for 35 rolling of the cans relative to a moving carrier so as to reduce the friction between the cans and carrier to a minimum if it becomes desirable to retain the cans in the tank for a longer period of time than that required for the cans to travel from the inlet 40 to the outlet of the tank.

Another object is to minimize wastage of 45 steam due to introduction of the cans to the cooking tank and exit of the cans therefrom.

Other objects and advantages may appear 50 in the subjoined detail description.

The accompanying drawings illustrate the invention.

Figure 1 is a sectional elevation, on irregular line indicated by x^1-x^1 , Fig. 2, of 55 a device embodying the invention.

Fig. 2 is a plan section on line indicated by x^2-x^2 , Fig. 1.

Fig. 3 is a plan view of Fig. 1.

Fig. 4 is a fragmentary elevation partly in section on line indicated by x^4-x^4 , Fig. 3. 55

Fig. 5 is a fragmentary developed sectional elevation on line indicated by x^5-x^5 , Fig. 2.

Fig. 6 is a fragmentary developed sectional elevation on line indicated by x^6-x^6 , Fig. 2. 60

Fig. 7 is a sectional elevation of the exit valve shown in Figs. 1 and 2.

Fig. 8 is a fragmentary developed sectional elevation on line indicated by x^8-x^8 , Fig. 3. 65

Fig. 9 is a sectional elevation of a different form of valve than those shown in Figs. 1, 2, 3 and 7.

There is provided a tank or stuffing box 70 comprising a side plate 1; preferably cylindrical, a top plate 2 fastened by bolts 3 to the side plate, and a bottom plate 4 fastened by bolts 5 to the side plate. The bottom plate 4 rests on a suitable support such as 75 a base 6 having legs 7.

The tank is provided with an inlet 8 in the top plate 2 and is provided with an outlet 9 in the side plate 1 and is also provided in its interior with a frame to 80 strengthen the same, said frame comprising in this instance top and bottom grids 10, 11 and standards 12 bolted to the top and bottom grids.

The bottom grid is provided with a socket 85 13 to accommodate the lower end of a central shaft 14 which extends through a central orifice 15 in the top plate 2.

The interior of the tank is provided with alternatively arranged superposed disks 16, 90 17, the disks 16 being provided with central orifices 18 and the intermediate disks 17 being bolted or otherwise fastened to sleeves 19 which are fastened by pins 20 or equivalents to the shaft 14. 95

Means are provided to drive the disks 16, 17 in opposite directions and in the instance shown the disks 16 are provided on their under faces and the disks 17 on their upper faces with bevel gear teeth 21 meshing 100 with bevel pinions 22 mounted on the inner ends of shafts 23 journaled in bearings 24 of the standards 12, said bevel pinions being arranged in four vertically aligned

groups. The shafts 23 are provided with collars 25, said collars having their inner faces abutting against the edges of the disks 16, 17 to prevent lateral shifting of the disks 16; and the shafts 23 of one group of bevel pinions 22 are provided with spur gears 26. The under surfaces of the disks 17 engage idler rollers 27 mounted on the inner ends of idler shafts 28, which are journaled in bearings 29 of the standards 12, there being spur pinions 30 rotatably mounted on some of the idler shafts and meshing with the spur gears 26 so that the spur gears and spur pinions all together form a gear train. It is thus seen that the bevel pinions 22 and idler rollers 27 form rolling supports for the peripheral margins of the disks 16, 17 respectively.

One of the shafts 23 having one of the spur gears 26 is provided with an extension 31 passing through a gland 32 of the side wall 1, said extension having on its outer end suitable driving means as a pulley 33 designed to be engaged by a belt, not shown. For the disks 16, 17 there are provided spiral runways 34 formed by spiral guides 35 spaced apart from said disks and riveted or otherwise fastened to supporting plates 36, alternate supporting plates having hubs 37, 37' surrounding the shaft 14, the lower ends of said hubs 37 resting on the upper ends of the collars 19 and the lower ends of the hubs 37' resting on the upper ends of the hubs 37 so as to support the runway plates, there being one of said spiral runways between the disks of each pair of disks 16, 17, and said guides projecting downward from the plates to within a slight distance of the upper surfaces of the disks 17.

The spirals of the different disks may be of duplicate construction, as shown.

Means are provided to guide cans from the inner ends of the runways of the disks 16 to the inner ends of the runways of the disks 17 and said guide means are constructed as follows: Each runway 34 of the disks 16 is provided at its inner end with a chute having a top 38 flush with one of the adjacent stationary plates 36 and bent downwardly and outwardly to form a curved end wall 39, said chute also having side walls 40, 41 fastened to the guide 35 to form an inward extension of the runway and said chute having a downwardly and inwardly sloping floor 42 flush at its outer edge with its disk 16 and spaced apart at its inner edge from the end wall 39 to form a port 43.

Means are provided to guide cans from the outer ends of the runways of the disks 17 to the outer ends of the runways of the disks 16 and said guide means are constructed as follows:

Each of the runways of the disks 17, excepting the bottom disk, is provided at its outer end with a chute having a top 44 flush

with its adjacent stationary plate 36 and bent downwardly and inwardly to form a curved end wall 45, said chute also having downwardly and inwardly sloping side walls 46, 47 fastened to the guide 35 to form an outward extension of the runway and said chute having a downwardly and outwardly sloping floor 48 flush at its inner edge with its disk 17 and spaced apart at its outer edge from the end wall 45 to form a port 49 so that cans rolling down the floor will roll from said floor through said port and down said end walls, to the bottom 50 of the chute and thence to the upper surface of the disk 16 next below.

The tank is provided with entrance and exit valves which will now be described.

The shaft 14 is provided on its upper end with a cylindrical valve 51 having pockets or compartments 52 open at top and bottom and closed on all sides, each pocket holding one can. The pockets receive cans a from a spout 53 and roll said cans on the top 2 through a segmental valve casing 54 closely fitting the top and sides of the valve and supported on the tank by brackets 55 and open at its bottom.

The top of said casing is provided near one end with a steam inlet port 56 and is provided near its opposite end and at intervals corresponding to the spacing of the pockets 52 with exhaust ports 57, all of said ports being interconnected by a manifold 58.

Other means than the shaft 14 may be provided for driving the valve 51 and in the instance shown in the drawings, said valve is provided at its rim with spur gear teeth 59 meshing with a spur pinion 60 mounted on a jack shaft 61 which is journaled in a bearing 62 mounted on the top of the tank and which is provided on its outer end with a sprocket 63 connected by a sprocket chain 64 with a sprocket wheel 65 that is mounted on the driving shaft extension 31.

The bottom disk 17 and its associated runway 34 discharge through a downwardly and outwardly inclined spout 66 into a cylindrical valve casing 67 which is provided with a cylindrical valve 68 having pockets 69 in its periphery, said valve being turned by a shaft 70 having a pulley 71 connected by a belt 72 to a pulley 73 that is mounted on the shaft extension 31.

The valve casing 67 may be provided at one side as in Fig. 7, with a port 74 and on its opposite side with ports 75 spaced apart to correspond with the spacing of the pockets 69, said ports inter-communicating with one another through a manifold 76, or said valve casing may be provided, as in Fig. 9, with diametrically opposite ports 77 interconnected by a tube 78, there being but four pockets in Fig. 9 whereas in Fig. 7 there are six pockets, the advantage of the greater number of pockets and ports being that some

of the steam will condense in the pockets and discharge, as water, with the cans through the valve outlet 79.

If the device is to be used for cooking the contents of the can, steam from a suitable source of supply, not shown, passes through a feed pipe 80 to a perforated coil 81 mounted in the lower end of the tank.

In practice if it is desired that the device be used as a continuous cooker, with steam under pressure, the valve 82 will be opened to admit steam from the feed pipe 80 through the steam coil 81 to the interior of the tank and power derived from a suitable source will be applied through a belt, not shown, to the pulley 33 to turn the disks 16, 17 in opposite directions, and to turn the valve 51 in the direction of the arrow 83, Fig. 3.

Then cans *a* will be fed into the spout 53 and will gravitate to the pockets 52, and said cans will then be automatically rolled by the valve 51 through the valve casing 54, and will drop through the inlet 8 and roll down a chute 84 through an orifice 85 in the upper runway plate 36 to the upper disk 16. As the valve 51 turns, the cans one by one drop onto the upper disk 16 and are carried by said disk in a circular path, the runway 35 gradually forcing the cans radially inward toward the shaft 14. Thus the cans will be forced close together to form a continuous spiral chain of cans extending from the inner end of the upper runway 34 to the outer end of said runway.

Steam that has passed from the tank through the inlet 8 into the adjacent pocket 52 of the valve 51 will be carried along by said pocket to the port 56 and will then expand through the manifold 58 and ports 57 into other of the pockets 52 containing cans, thus saving a certain per cent. of the steam, for the pressure tends to become equalized in those pockets that are interconnected by the manifold.

When the cans reach the inner end of the upper runway 34, the curved chute wall 40 will force the cans off of the upper disk 16 onto the sloping floor 42 and the cans will roll down said floor through the port 43 and be guided by the end wall 39 in a reverse direction onto the next lower disk 17. Said cans will then be carried by the said disk 17 outward from the shaft 14 and will gradually be forced radially outward by the appropriate runway guide 35 toward the periphery of said disk 17 until the curved chute wall 46 is reached, said curved wall forcing the can off of the disk 17 onto the sloping chute floor 48. The cans roll down said floor through the port 49 and are guided by the end wall 45 in a reverse direction onto the chute floor 50 and thence to the next lower disk 16, which then carries the cans toward the shaft 14 in the same way

as above described in connection with the upper disk 16.

Thus the cans will be carried in superposed paths alternatively by the disks 16, 17 toward and from the shaft 14 from the inlet 8 to the spout 66 and said cans will then roll down said spout; and as the valve 68 turns, the cans will drop one by one into the adjacent pocket 69 and will be carried by the valve 68 in the direction of the arrow 86, Figs. 7 and 9, to discharge through the valve outlet 79 into any suitable receptacle, not shown.

Pressure of the steam will be equalized by the manifold 76, Fig. 7, or by the tube 78, Fig. 9.

From the foregoing it is clear that assuming the contents of the cans are to be cooked for a definite interval of time, for instance, forty minutes, the belt 72 will not be connected up to the pulley 73 until the interval of forty minutes has passed. This is possible because, even if the first can entering the inlet 8 should reach the spout 66 before the desired interval of time has elapsed, the cans held back by the non-rotating valve 68 will be caused to revolve on the turning disks 16, 17, and thus held bodily stationary relative to the tank, and when the desired interval of time has elapsed the belt 72 will be brought into engagement with the pulley 73 to turn the valve 68 and release the cans one at a time from the tank.

If the device is to be used as an exhaust box, instead of feeding steam to the tank, air will be exhausted through the coil 81 by any suitable means, not shown, and the valves will operate in the same manner as above described to minimize the amount of air admitted to the interior of the tank when the cans enter and are discharged therefrom.

If the device is to be used as a continuous cooker to cook food stuffs such as fruits not requiring steam under pressure, the valves may, of course, be omitted.

A valve 87 may be provided to exhaust steam from the tank when desired.

What I claim is:

1. A can-conveyer comprising superposed disks, means to turn adjacent disks in opposite directions, and means to guide cans carried by the disks from the central portion of one disk to the periphery of a second one of said disks and from the periphery of the second disk to the central portion of said second disk.

2. A can-conveyer comprising superposed disks, means to turn adjacent disks in opposite directions, and means to guide cans carried by the disks from the periphery of one disk to the central portion of a second one of said disks and from said central portion to the periphery of said second disk.

3. A can-conveyer comprising superposed disks, means to turn said disks, a spiral run-

way mounted above each disk, and means to guide cans from one spiral runway to another.

4. A can-conveyer comprising superposed disks, means to turn said disks, a stationary spiral runway mounted above each disk, and means to guide cans from one spiral runway to another.

5. A can-conveyer comprising superposed disks, means to turn said disks in opposite directions, a spiral runway mounted above each disk, and means to guide cans from one spiral runway to another.

6. A can-conveyer comprising superposed disks, means to turn said disks in opposite directions, a spiral runway stationarily mounted above each disk, and means to guide cans from one spiral runway to another.

7. A can-conveyer comprising superposed disks, means to turn the disks, and means to guide cans carried by the disks from the central portion of one disk to the periphery of a second one of said disks and from the periphery of the second disk to the central portion of said second disk.

8. A can-conveyer comprising superposed disks, means to turn the disks, and means to guide cans carried by the disks from the periphery of one disk to the central portion of a second one of said disks and from said central portion to the periphery of said second disk.

9. A can-conveyer comprising superposed disks, the upper disk having a central orifice, means to turn said disks in opposite directions, a spiral runway for each disk, and means to guide cans from the inner end of the runway of the upper disk through said central orifice to the inner end of the runway of the lower disk.

10. A can-conveyer comprising superposed disks, the intermediate disk having a central orifice, means to turn said disks in opposite directions, a spiral runway for each disk, means to guide cans from the inner end of the runway of the upper disk through said central orifice to the inner end of the runway of the intermediate disk, and means to guide cans from the outer end of the runway of the intermediate disk to the outer end of the runway of the lower disk.

11. A can-conveyer comprising a tank having an inlet and an outlet, and means to move a can in superposed spiral paths from said inlet to said outlet.

12. A can-conveyer comprising superposed disks, gear teeth on the adjacent faces of said disks, runways for said disks, a gear meshing with the gear teeth on the disks, and means to turn said gear.

13. A can-conveyer comprising superposed disks, the upper disk having a central orifice, means to turn said disks, a spiral runway for each disk, and means to guide cans from

the inner end of the runway of the upper disk through said central orifice to the inner end of the runway of the lower disk.

14. A can-conveyer comprising superposed disks, runways for said disks, rolling supports at the margins of said disks, shafts for said rolling supports, collars on alternate shafts having their inner faces abutting against the edges of said disks, and means to drive one of said rolling supports.

15. A can-conveyer comprising a tank, a vertical central shaft mounted on the bottom of the tank, superposed disks in the tank, alternate disks having central orifices and the disks between said alternate disks being provided with sleeves fastened to the shaft, plates arranged above each disk, said plates having hubs, the hubs of the plates above the orificed disks resting on the other hubs, and said other hubs resting on the upper ends of the collars, spiral guides extending downward from the plates, and means to turn the disks in opposite directions.

16. A can-conveyer comprising a tank having an inlet and an outlet, means in the tank to carry and guide cans from the inlet to the outlet, a cylindrical valve rotatably mounted on the top of the tank and provided with pockets open at top and bottom, a valve casing mounted on the tank adjacent the inlet and provided with ports, a manifold communicating with said ports, means to turn said valve, and an exit valve at the outlet.

17. A can-conveyer comprising a tank having an inlet and an outlet, means in the tank to carry and guide cans from the inlet to the outlet, rotatably mounted cylindrical valves having pockets, casings covering some of said pockets and communicating with the inlet and outlet respectively, said casings having ports communicating with different pockets of the valves respectively as said valves turn, manifolds connecting the ports of the respective casings, and means to turn said valves.

18. The combination with a tank, of a valve casing provided with ports, a cylindrical valve rotatably mounted to turn in the casing and provided with pockets communicating with the ports successively as the valve turns, a spout communicating with the interior of the casing at a point midway circumferentially between said ports, and communicating with the interior of the tank, a tube interconnecting said ports, an outlet from the casing, and means to turn the valve.

19. The combination with a tank, of a valve casing communicating with the interior of the tank and provided with ports, a cylindrical valve rotatably mounted to turn in the casing and provided with pockets communicating with the ports success-

- sively as the valve turns, a tube inter-connecting said ports, an outlet circumferentially in the valve casing between said ports, and means to turn the valve.
- 5 20. In combination, disks, means to turn the disks in opposite directions, spiral runways for the disks respectively, and a chute connecting the inner end of one runway to the inner end of another of the runways.
- 10 21. In combination, disks, means to turn the disks in opposite directions, spiral runways for the disks respectively, and a chute connecting the outer end of one runway to the outer end of another of the runways.
- 15 22. In combination, superposed disks, means to turn the disks in opposite directions, spiral runways for the disks respectively, and a chute having curved sides forming an extension of the sides of the upper
- 20 one of said runways, said chute having a curved end wall and having a sloping floor flush with the edge of the upper disk and spaced apart from the end wall to form a port.
- 25 23. A can-conveyer comprising superposed disks, the intermediate disk having a central orifice, means to turn said disks, a spiral runway for each disk, means to guide cans from the inner end of the runway of the upper disk through said central orifice to the inner end of the runway of the intermediate disk, and means to guide cans from the outer end of the runway of the intermediate disk to the outer end of the runway of the lower disk.
- 30 24. In combination, disks, means to turn the disks, spiral runways for the disks respectively, and a chute connecting the inner end of the one runway to the inner end of another of the runways.
- 35 25. In combination, disks, means to turn the disks, spiral runways for the disks respectively, and a chute connecting the outer end of one runway to the outer end of another of the runways.
- 40 26. In combination, superposed disks, means to turn the disks, spiral runways for the disks respectively, and a chute having curved sides forming an extension of the sides of the upper one of said runways, said chute having a curved end wall and having a sloping floor flush with the edge of the upper disk and spaced apart from the end wall to form a port.
- 45 27. In testimony whereof, I have hereunto set my hand at Los Angeles, California, this 22nd day of April, 1915.
- 50 HENRY C. PRIVETT.
